(57) CLAIM

The ornamental design for a folding table, as shown and described.

DESCRIPTION

FIG. 1 is a front perspective view of a folding table showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom plan view thereof;

FIG. 7 is a top plan view thereof;

FIG. 8 is a bottom perspective view thereof, shown in an alternate configuration of use; and,

FIG. 9 is a bottom perspective view thereof, shown in a second alternate configuration of use.

The broken lines throughout the drawing figures depict portions of the folding table that form no part of the claimed design.
